[57] CLAIM

The ornamental design for a hoist chair, as shown.

DESCRIPTION

FIG. 1 is a perspective view of a hoist chair, showing my new design in raised position;

FIG. 2 is a left side elevational view in a lowered position thereof;

FIG. 3 is a top view thereof;

FIG. 4 is a bottom view thereof;

FIG. 5 is a front elevational view in the raised position thereof;

FIG. 6 is a right side elevational view in the raised position thereof;

FIG. 7 is a left side elevational view in the raised position thereof; and,

FIG. 8 is a rear elevational view in the raised position thereof.
